US00D810399S

(12) **United States Design Patent** (10) **Patent No.:** **US D810,399 S**
(45) **Date of Patent:** **** Feb. 20, 2018**

(54) **GOWN**

(71) Applicant: **The New York Hospital Medical Center of Queens**, Flushing, NY (US)

(72) Inventor: **Terence Michael Brady**, Bellerose Village, NY (US)

(73) Assignee: **New York-Presbyterian/Queens**, Flushing, NY (US)

(**) Term: **15 Years**

(21) Appl. No.: **29/545,736**

(22) Filed: **Nov. 16, 2015**

Related U.S. Application Data

(62) Division of application No. 29/397,967, filed on Jul. 25, 2011, now Pat. No. Des. 743,143, which is a division of application No. 29/378,768, filed on Nov. 9, 2010, now Pat. No. Des. 641,957, which is a division of application No. 29/354,984, filed on Feb. 1, 2010, now Pat. No. Des. 626,721, which is a division of application No. 29/299,313, filed on Dec. 21, 2007, now Pat. No. Des. 608,980.
